UNITED STATES PATENT OFFICE.

HORACE K. JONES, OF HARTFORD, CONNECTICUT, ASSIGNOR TO THE RUSSELL & ERWIN MANUFACTURING COMPANY, OF NEW BRITAIN, CONNECTICUT.

MACHINE FOR HEADING SCREW-BLANKS.

SPECIFICATION forming part of Letters Patent No. 574,609, dated January 5, 1897.

Application filed October 12, 1895. Serial No. 566,489. (No model.)

To all whom it may concern:

Be it known that I, HORACE K. JONES, a citizen of the United States, residing at Hartford, in the county of Hartford and State of Connecticut, have invented certain new and useful Improvements in Machines for Heading Screw-Blanks, of which the following is a specification.

My invention relates to machines for heading screw-blanks; and the objects of my improvement are simplicity and economy in construction, general efficiency and convenience of operation, and the rapid production of well-formed blanks.

15 In the accompanying drawings, Figure 1 is an elevation of my machine, showing one of the longest sides. Fig. 2 is an end view. Fig. 3 is an elevation showing the opposite side from that shown in Fig. 1. Fig. 4 is a plan view. Fig. 5 is a longitudinal section of the main parts of the same on the line *x-x* of Fig. 4. Fig. 6 is a like view of parts on the line *y-y* of Fig. 4. Fig. 7 is a rear view of the ram with the pitman removed. Fig. 8 is an enlarged transverse section on the line *u-u* of Fig. 4. Fig. 9 is a horizontal section, partly in plan view, of parts of my machine, on the line *v-v* of Fig. 1, on the same scale as Figs. 1 to 6. Fig. 10 is a vertical section of parts 30 on the line *z-z* of Fig. 4. Fig. 11 is an enlarged elevation of parts appertaining to the feed. Fig. 12 is a front elevation of the heading-punches and their holder, the upper ends of the holder being shown in vertical section 35 on the line *w-w* of Fig. 13. Fig. 13 is a horizontal section of the same on the line *n-n* of Fig. 12. Fig. 14 is an enlarged side elevation of one of the heading-dies, together with the end of the last heading-punch. Fig. 15 is an 40 end view of the heading-dies, and Fig. 16 is a view showing a portion of the reverse end of one of said dies.

A designates the frame of the machine; B, the driving-shaft; C, the driving-pulley on 45 said shaft, and D the cam-shaft. The main shaft is provided with the usual crank 15, Figs. 5 and 9, connected with the longitudinally-reciprocating ram E by means of the pitman 14. The ram E is connected with the 50 pitman through its adjustable block 16, which

may move longitudinally in the ram on suitable ways or guides. This block is supported or backed, to make it solid with the other parts of the ram, by means of the wedge 17, whose threaded shank 18 extends through the 55 top of the ram, where it is provided with an adjusting-nut 19. By loosening the wedge 17 the sliding block may be pushed farther into the ram to shorten the same and thereby adjust the position of the heading-punches 20 60 21 22 relatively to their stroke, and the nut and wedge may be used for adjusting the sliding block in the ram when said block is moved outwardly to lengthen the ram. In suitable guides in the front end of the ram is the 65 punch-holder 23, arranged to slide vertically in suitable ways.

In the middle of the die-holder at the front is a dovetailed recess 24 to receive the punch-holding blocks 25, arranged in pairs, with 70 their outer side faces beveled to correspond with the beveled side walls of the punch-holding recess, while their confronting faces are grooved to correspond to the shape of the shanks of the several heading-punches. I 75 have shown these shanks as square in cross-section, but they may be of any desired form.

Above the pairs of punch-holding blocks I place a cap-block 26 to fill the recess above 80 said blocks, and I secure the same in place in any proper manner, for example, by a bolt 27, which bears on the top of said block. The several pairs of punch-holding blocks and the heading-punches within said blocks are held in place laterally by means of the set-screws 85 28, set in the punch-holder so as to stand approximately at right angles to the beveled side faces of the die-blocks. These set-screws not only firmly hold the heading-punches, but by loosening the set-screw at one side of a 90 pair of blocks and tightening the one on the opposite side the heading-punches may be adjusted laterally in either direction, as may be desired.

The driving-shaft B and cam-shaft D are 95 connected, by means of the gear-wheel 29 on shaft B and gear-wheel 30 on shaft D, with teeth in the proportion of one to three, the former wheel having twenty and the latter sixty teeth, whereby the driving-shaft makes 100

three revolutions for every revolution of the cam-shaft, so that the ram makes three strokes in heading each blank. In thus making three strokes it is necessary to vary the height of the heading-punches at each successive stroke in order to bring them into proper alinement with the blank in the heading-dies 31. At the lower end of the punch-holder 23 I secure a spring 91, the other end of said spring being secured to some suitable stationary support, as, for example, the pan or floor under the machine, said spring having a constant tendency to pull and hold the punch-holder down as far as its stops will permit it to fall. The lowermost position of the punch-holder to bring the first punch 20 in front of the heading-dies at the first stroke of the ram in forming a head is governed by the adjusting-screw 40, the lower end of which then rests upon the top of the ram E.

The height of the punches 21 and 22 is regulated by cams, levers, and screws. The cam 36 on the cam-shaft D acts upon the lever 37 to bring its farther end-face into a horizontal plane. In the punch-holder is an adjusting-screw 38, the lower end of which may rest upon the end face of said lever and thereby bring the punch-holder to its next highest or medium position, with the punch 21 in alinement with the heading-dies for the second stroke of the ram in forming a head. The lever is raised to bring the holder to approximately the proper height by the cam 36, and the screw 38 enables the height to be more nicely adjusted. A set-nut 35 may be applied to said screw to lock it in its adjusted position. A similar cam 32 on the cam-shaft D acts upon the lever 33 in like manner to bring the punch-holder to its highest position and the last punch 22 into alinement with the heading-die for the third and last stroke in forming a head. A like adjusting-screw 34, provided with a set-nut 35, bears upon the end of the lever, as before described, for the lever 37 and screw 38. The levers 33 and 37 may be provided with proper shoes at either or both ends to prevent wear, although I have shown shoes 39 only at one end thereof.

So much of the machine as has been thus far described may be used in connection with any known heading-dies and feed, but I prefer to employ the particular dies 31 herein shown, which form cutting-off and pointing dies, as well as the dies which give form to the headed blank. These are divided dies or dies formed of two blocks with recessed faces, commonly known as "open dies," the recesses of two confronting faces forming the proper cavity for the headed blank. These dies are shown by themselves in Figs. 14, 15, and 16, in which 41 designates the conical cavity for the head, 42 a short cylindrical shank-cavity, 43 the cylindrical cavity to form the body of the screw-blank, the same being preferably of a little less diameter than the shank-cavity, while 44 is the conical cavity for the pointed end of the blank.

Adjacent to the conical cavity the faces of the die-blocks are beveled off, as at 45, to bring the side walls of the cavity at that end to a chisel edge. The die-blocks are also recessed transversely to the conical head-cavity, as at 46, so that a transverse slot is formed through the top or outer end of the head-cavity, as shown. I also bevel off each corner of both die-blocks, as at 47.

For convenience and to economize in stock I form the proper die-cavities in each of the four side faces of the die-blocks, but this is not essential. These dies are placed in a transverse groove of the die-holder 48, which may be arranged for adjusting vertically in any proper manner, and suitable caps 49 may partly cover the front or outer ends of the die-blocks to keep them from working forwardly out of the recess in the die-holder. I also prefer to employ filling-blocks 50 for filling out the recess in the die-holder. A tube 89, Fig. 5, extends down through the die-holder 48 to the top of the dies 31, directly over their confronting faces, and this tube is connected in any ordinary manner with an air-supply for conducting an air-blast down through the space between said dies whenever they are opened. At the left-hand end of the dies, Fig. 8, in the frame A there is a tubular adjusting-screw 51, within which is a holding-rod 52, carrying a collar-block 53 between the end of said screw and the filling-block on that side of the dies. This holding-rod prevents the collar-block from falling down out of place, and said rod may be held in place by a spring or button 54 on the frame of the machine. The tubular adjusting-screw 51 may be secured against accidental displacement by means of the set-nut 90. The die-block on this side, when properly set is to remain stationary.

Extending obliquely through the die-block to the beveled-off corner 47 of the other die is a sliding rod 55, that is pressed upon by a spring 56 with a constant tendency to separate the two dies. On the other side of the dies, the right-hand side in Fig. 8, is the die-closing slide 57, having a screw-adjustable stop 58 for striking against the frame A to limit the outward movement of said slide, whose outer end is provided with a wedge or cam 59.

The die-closing rollers 60 61 are mounted in a sliding block 63, which is integral with the roller-slide 63, said slide being guided at one end by the bracket 64 on the frame of the machine, and at the other end by the bearing-block 65 on the frame of the machine, and through which the cam-shaft D passes. The back of the gear-wheel 30 is recessed to form the internal cam 66, Fig. 10, which acts upon the friction-roller 67 of the roller-slide for moving said slide in one direction, while the cam 68 acts upon the companion friction-roller 69 for moving the roller-slide in the other direction. The die-closing rollers carry the gear-wheels 70, one of which engages the

stationary rack 71 on the frame A, whereby said die-closing rollers are caused to roll while being reciprocated in front of the wedge or cam 59 of the die-closing slide 57, said slide 5 being released and the dies permitted to open when said rollers are opposite the thinner part of said wedge and closed when the axis of the die-closing rollers are substantially in alinement with the axis of the die-closing 10 slide, as shown in Fig. 9.

The feed-rollers 72, ratchet-wheel 73 on one of the feed-roller shafts, the pawl or pawls 74, vibrating pawl-carrier 82, its operating pitman 75, and crank 76 are of an ordinary construction considered by themselves, but in connection therewith I employ the pawl-lifting lever 77, which is journaled on the set-nut 90 and is moved in one direction by the cam 78 on the cam-shaft D and in the opposite direction 20 by the spring 79. One end of this lever 77 lies adjacent to the ratchet-wheel 73 and is curved on a radius about equal to the radius of said wheel. When the lowest part of the cam 78 is in contact with that end of the 25 pawl-lifting lever, the curved end thereof falls so low that the pawl or pawls are permitted to engage the ratchet-wheel for operating the feed; but when the higher and concentric portion of said cam is in contact with 30 said lever the curved end thereof is raised, as most clearly shown in Fig. 11, so as to throw the pawl or pawls out of action, although the movement of the pawl-carrier is continuous. Inasmuch as the shaft carrying the crank 76 35 for operating the pawl-carrier also carries the crank for operating the ram and makes three revolutions to one of the cam-shaft, and the cam 78 is concentric for about two-thirds of its periphery, the pawl-carrier acts to move 40 the feed-rollers at only one stroke out of three, that is to say, there are two idle strokes of the pawl-carrier for every feeding stroke, thus permitting the ram to give three strokes upon every blank fed to the heading-dies and 45 also giving the feed-rollers a quick movement. The ram is driven by a continuously-moving crank-shaft to complete its strokes at regular intervals, the feed acting quickly after the completion of a series of three strokes and 50 before the completion of the first blow in a second series of strokes can be made, so that the ram is not stopped between said series of strokes for the purpose of giving time to feed the wire. The pawl-lifting lever is provided 55 with a pin or projection 80, which may be engaged by the hooked end of the retaining-lever 81 to hold the pawls wholly out of action whenever it may be desired to stop the feed entirely without stopping the machine.

60 In connection with the dies slotted transversely through the head-cavity, as before described, I provide the last heading-punch 22 with a slot-swaging blade 82, the length of which is substantially equal to the diameter 65 of the head-cavity of the heading-dies, said blade standing in alinement with the slot 46 through the dies, whereby as the slot in the

head is swaged the metal is forced outwardly from the head and into the slot 46, forming a wing or projection at each end of the slot in 70 the headed blank. In order to remove this wing or projection and perfect the slot in the head, I employ the reciprocating clearing-tool 83. It is mounted on the rocking-arm 84 of the rock-shaft 85. Said arm and clearing-tool 75 are forced downwardly by means of the spring 86 and upwardly by the cam 87 on the cam-shaft D, acting on a projection at the end of the connecting-rod 88, one end of which rod is secured to an arm on the rock-shaft 85, as best 80 shown in Fig. 1.

Immediately after the feed-rollers 72 act to feed the proper length of wire the cam 68 acts to move the roller-slide 63 and block 62 to carry the die-closing rollers 60 61 to the position shown in Fig. 9, the rack 71 and gears 70 giving said rollers a rolling motion to carry the roller 60 over the wedge or cam 59 as they come into place, so that the die-closing slide 57 is forced against the moving one of the dies 90 to close them firmly upon the wire. The moving die in thus coming into place severs the wire, and the sharpened or chisel-like edges at the pointed end of the die-cavity cut a chip from each side of the wire opposite the pointed blank, and the metal left between the chipped sides and within the conical cavity 44 is swaged to form the pointed end of the blank. At the first stroke of the ram after the feed has acted the cams 32 36 and levers 33 37 100 will be in a position to let the punch-holder down to its lowermost position to bring the first punch 20 directly in front of the heading-dies to act upon the wire and partially form the head. This punch may be recessed or 105 made a little short, so as to leave something for the other punches to do. At the second and third stroke of the pawl-carrier the pawl or pawls are held out of action by the cam 78 and lifting-lever 77, which will so hold the 110 pawls until the ram has made a series of three strokes and then release the pawls in time to have the feed act before the ram makes the first stroke in its next series. At the second stroke of the ram the cam 36 and lever 37 will 115 be in a position to cause the punch-holder to bring its second or middle punch 21 in front of the heading-dies to further perfect and nearly complete the head, and then the cam 32 and lever 33 in like manner elevate the 120 punch-holder to bring the third and last punch 22 in front of the heading-die at the third stroke of the ram to finish the head and swage the screw-driver slot therein. The recess in the cam 87 now comes opposite the bearing-point or projection of the connecting-rod 88, so that the spring 86 is permitted to force the clearing-tool 83 quickly down through the transverse slot in the heading-die and the headed blank, thereby removing the metal at 125 the ends of the slot in said blank. The continual rotation of the cam 87 returns the clearing-tool to its former position. The recess or lower portion of the cam 68 now comes in front 130

of the roller 69 and the cam 66 acts to withdraw the die-closing roller from in front of the die-closing slide and its wedge, so that the spring 56 and sliding rod 55 may act to open the dies, 5 the headed blank may fall therefrom, and the air-blast constantly flowing through the tube 89 will blow away the chips or other matter from between the dies 31, ready for them to close upon the wire again to have the operations hereinbefore described repeated in the production of other blanks. As the die-closing rolls 60 61 are removed from the die-closing rod 57 the spring 46 and rod 55 push the movable die 31, block 50, and rod 57 outwardly until the screw 58 strikes the inner side of the frame of the machine. By means of this screw the distance to which the dies 31 are separated is accurately regulated.

I have shown and described the heading-dies and the last heading-punch in the preferred form and in a form that is adapted for use in combination with other parts, but I wish to make use of said illustration and description only for the purpose of laying a proper foundation for claims to the combination of said dies and punch, or either of them, with other parts of the machine, having by amendment divided this application so as to confine what remains of it to the machine, 30 while the dies and punch having the slot-forming blade, considered by themselves, form the subject-matter of another application, Serial No. 574,973, filed January 10, 1896.

It will also be observed that other heading-dies, when substituted in the combinations pointed out in the claims so as to operate the same in the combination, will be considered the equivalent of those herein shown.

I claim as my invention—

1. The combination of the punch-holder having a recess with the several punches and pairs of punch-holding blocks with screw-seats on their outer side edges, a holding-cap and the screws 28 for holding and adjusting said punches laterally, substantially as described and for the purpose specified.

2. The combination of the reciprocating ram, a punch-holder mounted on said ram, and two or more independent sets of levers and cams acting at different times for elevating said punch-holder to different heights for different strokes of the ram, substantially as described and for the purpose specified.

3. The combination of the reciprocating ram, a punch-holder mounted on said ram, levers, cams, and separate adjusting-screws for regulating the height of the punch-holder at each of its different strokes, substantially as described and for the purpose specified.

4. The combination of the reciprocating ram, the punch-holder mounted to slide vertically on said ram, means for moving said ram vertically, and adjusting-screws 34, 38 and 40 extending to the top of the ram for adjusting the height of the punch-holder at different strokes, substantially as described and for the purpose specified.

5. The combination of a ram, a punch-holder mounted on said ram, the continuously-rotating crank-shaft directly connected with said ram by a pitman, the cam-shaft connected with said crank-shaft for rotating in the proportion of three to one, and means for holding the punch-holder at different heights for three successive strokes of the ram, substantially as described and for the purpose specified. 70 75

6. The combination of the die-closing slide having cam or wedge with the die-closing rollers geared together, the rack 71, roller-slide in which said rollers are mounted, and the cam for reciprocating said roller-slide, substantially as described and for the purpose specified. 80

7. The combination of the heading-dies 85 with the die-closing slide having cam or wedge at one end, geared rollers and rack, and means for rolling said rollers against said cam or wedge to close said dies for cutting off and pointing one end of the wire preparatory to 90 heading the other end, substantially as described and for the purpose specified.

8. The combination of the feed-rollers, the ratchet-wheel for driving them, the pawl-carrier and pawl for acting on said ratchet-wheel, means for moving the pawl-carrier and means for lifting and holding the pawl out of action during certain strokes of the pawl-carrier, substantially as described and for the purpose specified. 95 100

9. The combination of the ram, its driving-shaft, the punch-holder and punches on said ram, the cam-shaft connected with said driving-shaft to rotate in the proportion of three to one, the heading-dies, the feed-rollers, the ratchet-wheel, the pawl-carrier and pawl, the pitman for driving said pawl-carrier, a crank on said driving-shaft for driving said pitman and pawl-carrier, a pawl-lifting lever and a cam on the cam-shaft for regulating the action 110 of said lifting-lever to make the continuously-moving pawl-carrier feed only once for every three strokes of the ram substantially as described. 105

10. In a heading-machine, a die having the head-forming cavity slotted transversely, the punch having the slot-swaging blade in alignment with the transverse slot through said head-forming cavity, and a clearing-tool mounted to pass through said head-forming cavity to finish the slot in the headed blank, substantially as described and for the purpose specified. 115 120

11. In a heading-machine, the combination of the die-holder, the heading-dies having at one end the chisel-edge cutting-off and pointing cavity, and the air-blast tube in said die-holder with its end directed to the space between said dies at the cutting end, substantially as described and for the purpose specified. 125 130

12. In a heading-machine whose ram makes two or more blows in forming one head; the combination of a continuously-rotating crank-

shaft, a continuously-moving ram directly connected to said crank-shaft by means of a pitman, punches mounted on said ram to move therewith, and a cam-shaft geared to said crank-shaft and acting to move the punches into position for their successive operations on the head, substantially as described and for the purpose specified.

13. In a heading-machine, the combination of a ram carrying three punches, mechanism for presenting said punches consecutively to the heading-dies at equal intervals of time, and an intermittent feed which acts after each blow of the third punch and before the next blow of the first punch, the interval of time between each series of three strokes being the same as the interval of time between any two consecutive strokes in each series, substantially as described.
14. In a machine for heading blanks, the combination of a series of heading-punches carried on a ram, with a continuously-revolving crank-shaft, a pitman directly connecting said crank-shaft and ram, mechanism for consecutively presenting to the heading-dies the different punches in said series, and an intermittent feed operating between the last blow

of the last punch and the first blow of the first punch in said series of punches, the interval of time between said blows being equal to the interval between the blows of any two consecutive punches in said series, substantially as described.

15. The combination of a punch-holder, with the several punches and pairs of laterally-movable punch-holding blocks, means for binding the several pairs of blocks upon each other, and means for separately binding each pair of blocks upon its punch, substantially as described and for the purpose specified.

16. The combination of a punch-holder with the several punches and pairs of laterally-movable punch-holding blocks, means for binding the several pairs of blocks upon each other, and means for separately adjusting each pair of blocks and its punch laterally, substantially as described and for the purpose specified.

HORACE K. JONES.
